UNITED STATES PATENT OFFICE.

LOUIS B. FULTON, OF PITTSBURG, PENNSYLVANIA.

GAGE-COCK.

SPECIFICATION forming part of Letters Patent No. 297,923, dated April 29, 1884.

Application filed November 21, 1883. (No model.)

To all whom it may concern:

Be it known that I, LOUIS B. FULTON, of Pittsburgh, in the county of Allegheny and State of Pennsylvania, have invented certain new and useful Improvements in Gage-Cocks; and I do hereby declare that the following is a full, clear, and exact description of the invention, which will enable others skilled in the art to which it appertains to make and use the same, reference being had to the accompanying drawings, which form a part of this specification, in which—

Figure 1 is a central sectional view of a gage-cock provided with my improvement. Figs. 2 and 3 are transverse sectional views of the box *p* in Fig. 1. Fig. 4 is an end view of the box. Figs. 5 and 6 are respectively a side view and a central section of modifications.

This invention relates to gage-cocks; and it consists in the construction and combination of parts, substantially as hereinafter fully described and claimed.

My improvement is applicable to gage-cocks, whether closing with or against the pressure and rotating or not. Fig. 1 illustrates its application to a cock designed to close against the pressure.

A is the body of the cock, having thread *b*, for attachment to the boiler, and globe or bulb *c*. Body *A* is formed with the nozzle *d* projecting forward into the globe *c*, formed cylindrical outside, and at its ends shaped into an outwardly-sloping valve-seat, *e*, as shown; or the seat *e* may slope inwardly, like an ordinary valve-seat. A stuffing-box cap, *f*, screws onto the threaded outer end of body *A*, and admits through its central bore the stem *g*, having handle *h* and threaded enlargement *i*, which screws into the internally-threaded neck *k* of body *A*. Enlargement *i* has at its rear end a central recess, *m*, with a hard-metal seat, *n*, in its bottom. In recess *m* fits the pin *o*, which carries the cage-valve, consisting of a box, *p*, whose internal diameter is slightly larger than the external diameter of the cylindrical nozzle *d*, and at its rear end has the inwardly-turned flange *q*, substantially fitting said nozzle *d*. At the front end of the chamber of box *p*, I form the valve *s*. The length of cylindrical portion of nozzle *d* is such with reference to the movement of the valve in opening and closing that the flange *q* does not

move off the nozzle *d*, which therefore constitutes a guide for the valve and preserves its axial position. The same is true of the pin *o* 55 with reference to the recess *m*.

In the outer walls of box *p*, I form openings or ports *t*, for the escape of steam and water when the valve is open. If the valve is to rotate when opened, I form the openings or ports 60 *t* at an angle, as in Fig. 2, so that the escaping steam or water will strike the inclined walls of the ports and drive the valve in a rotary direction; otherwise I make the ports *t* simply radial, as in Fig. 3.

Instead of the angular ports *t*, cut or formed in the walls of box *p*, I may form inclined slits *t* in the lip or flange *q*, as in Fig. 4, for rotating the valve. In any of these the valve remains the same as before. In case of the closed globe *c*, the vent *v* is attached for escape of steam or water; but instead of the closed globe I propose an open cage or skeleton having the thread-fitting *b* and neck *k*, threaded as before, joined together by two or more arched 75 bars, *w*. In this case the stuffing-box may be dispensed with, as the steam escapes directly from valve and box *p*. This leaves the valve itself exposed to inspection while testing for water-level, so that its operation may be observed. Such construction is fully illustrated by Fig. 5.

Obviously the invention is applicable to a cock shutting with the pressure. Such form is shown by Fig. 6, where the valve-seat *e* and 85 valve *p* have their relative positions reversed, and the stem *o* projects outwardly through the outer portion of the body, as in an ordinary "Mississippi Gage-Cock."

I claim as my invention—

1. A gage-cock having an annular projecting valve-seat and a box surrounding the same, and constituting the valve, and provided with means of rotation under the force of escaping steam or water, substantially as 95 described.

2. A gage-cock having an annular projecting valve-seat with cylindrical body externally, and a box having an internal flange or two or more projections fitting said cylindrical body, and said box constituting the valve, substantially as described, whereby the valve is guided and centered.

3. In a gage-cock, the combination, with an

annular projecting valve-seat, of a valve having extended walls embracing and surrounding said seat, said walls having one or more angular ports, substantially as shown and described.

4. In a gage-cock, the combination, with an annular projecting valve-seat, of a valve having extended walls embracing and surrounding said seat, and provided with an angular port 10 or ports adapted to rotate said valve under the propulsive force of escaping steam or water, substantially as described.

5. In a gage-cock, the combination of the annular cylindrical valve-seat *e*, box-valve *s*, 15 having port or ports *t*, and guide-pin *o*, adapted

to aid in guiding said valve, substantially as described.

6. In a gage-cock, the combination, with the valve and valve-seat, of the boiler-fitting *b*, neck *k*, and bars or frame *w*, with the space 20 inclosed between said parts open and exposed, substantially as described.

In testimony that I claim the foregoing as my own I have hereto affixed my signature in presence of two witnesses.

LOUIS B. FULTON.
